UNITED STATES PATENT OFFICE.

GOTTLIEB YUNKER, OF NEWARK, NEW JERSEY, ASSIGNOR TO NEWARK CORNICE & SKYLIGHT WORKS, OF NEWARK, NEW JERSEY, A CORPORATION OF NEW JERSEY.

GRAVITY-LOCK.

No. 882,921.

Specification of Letters Patent. Patented March 24, 1908.

Application filed December 27, 1907. Serial No. 408,289.

To all whom it may concern:

Be it known that I, GOTTLIEB YUNKER, a naturalized citizen of the United States, and a resident of Newark, in the county of Essex 5 and State of New Jersey, have invented certain new and useful Improvements in Gravity-Locks, of which the following is a specification.

My invention relates to gravity locks for 10 windows; and particularly to a lock adapted to be used in connection with fire-proof windows of the swinging sash type, adapted to automatically close and lock when exposed to a temperature of sufficient intensity.

It has for its object a device which will 15 lock the sash at the top, does not project to any appreciable extent perpendicularly to the sash, and which is capable of a gravity adjustment. I attain these objects in the 20 lock illustrated in the accompanying drawings, in which—

Figure 1 is a side elevation of the window, partly in section and showing the sash in closed and open position, the latter position 25 being shown in dotted lines. Figs. 2 and 3 are partial front elevations on an enlarged scale, showing the sash in locked and unlocked position. Fig. 4 is a side elevation of the lock on an enlarged scale. Fig. 5 is a 30 view on an enlarged scale of the socket plates with sash removed.

Similar characters of reference designate corresponding parts throughout the several views.

Referring to the drawings, 10 designates a 35 sheet metal frame of the usual construction and to which is fitted a sheet metal sash 11, provided with wired glass window panes 12. This sash is pivoted to the frame in such a 40 manner as to be gravity closing, and when held open will automatically return to closed position if released.

13 and 14 are socket plates, the plate 13 being secured to the lintel of frame 10 as 45 shown; and the striking plate 14 to the plate 13, said plate 14 being slotted and thereby adjustable with respect to the other by means of the adjusting screws 15.

Respective openings 16 and 17 adapted to 50 register with each other, are provided in said plates; and by adjusting the plate 14 with respect to plate 13, the combined opening may be correspondingly varied. An opening 18 is also cut in the lintel of the frame 10, 55 and registers with the said combined open-

ing so as to permit a latch bolt 19 to pass through. This latch bolt passes through and is guided in a lock casing 20, being provided with an upper and a lower lug 21 and 60 22 adapted to act against the upper and lower wall of said casing, and thereby limit the vertical movement of said latch bolt. The lower end of this latch bolt extends beyond the casing 20, and is provided with a 65 projecting hook 23 and an eye 24. To the eye 24 is secured a chain 25 provided with the usual fusible connection (not shown) and adapted to be secured to some holding means as a hook 26 to hold the window sash 11 open. To the casing 20 is secured an 70 arm 27 pivotally supporting a lever 28, the inner arm of which is arranged to engage the hook 23, while the outer arm is provided with an adjustable weight 29 whose position is fixed with respect to said lever by means of 75 the thumb-screw 30.

When the sash is closed, the weight 29 through the action of the inner arm of the lever 28 against the hook 23 causes the latch bolt to be forced up into and through the 80 openings 16, 17, and 18 to lock said sash 11 to its frame 10. In order to open the window, the chain 25 attached to the latch bolt 18 is pulled downwardly in opposition to the action of the weight 29. This causes the 85 hook 23 to act against the inner arm of lever 28 thereby releasing the latch bolt from the socket plates 13 and 14, permitting the window sash to be swung inwardly to open the window. The chain is then fastened to the 90 chain hook 26 and will automatically part at a fusible connection should heat of sufficient intensity reach this point, causing the sash to close; and through the action of the weight 29 and lever 28, to lock the window 95 at the top.

My improved lock may be readily applied to window sashes; does not project in an unsightly manner in a direction perpendicular to said sash; and by means of the adjustable 100 weight, one uniform size of lock is applicable to various sizes and weights of window sashes.

I claim:—

1. In a window of the swinging sash type: a gravity lock for said window comprising, a 105 lock casing secured to the sash of said window; a latch bolt guided therein; means in connection with the frame of said window, adapted to receive said latch bolt to lock said window sash; and a lever provided with an 110

adjustable weight and adapted to normally cause said latch bolt to project beyond its said casing.

2. In windows of the swinging sash type:
- 5 a gravity lock for said window comprising, a lock casing secured to the sash of said window; a latch bolt guided therein and provided with an upper and a lower lug, adapted to act against the walls of said casing to limit
  - 10 the extent of vertical movement of said latch bolt; a hook integral with said latch bolt and outside of said casing; a lever piv-

totally connected to said casing, its inner arm being adapted to engage said hook and its outer arm provided with an adjustable 15 weight; and an eye at the lower end of said latch bolt.

Signed at Newark, in the county of Essex and State of New Jersey this 10th day of December A. D. 1907.

GOTTLIEB YUNKER.
